AUTOMOBILE

Virgil M. Exner, Birmingham, Mich., assignor to Chrysler Corporation, Highland Park, Mich., a corporation of Delaware

Filed July 5, 1960, Ser. No. 61,228

Term of patent 7 years

(Cl. D14—3)

FIG. 1 is a side elevational view of an automobile embodying my new design, the side opposite to that shown being substantially the same;

FIG. 2 is a front elevational view thereof;

FIG. 3 is a rear elevational view thereof;

FIG. 4 is a perspective view taken from the front of the automobile;

FIG. 5 is a perspective view taken from the rear of the automobile;

FIG. 6 is a sectional view taken on the line 6—6 of FIG. 1; and

FIG. 7 is an enlarged fragmentary view of the area designated by the broken circle 7 in FIG. 1.

The dominant features of my design reside in the full line portions of the drawings.

I claim:

The ornamental design for an automobile, substantially as shown and described.
